UNITED STATES PATENT OFFICE.

JOHN A. AULD, OF ERIE, PENNSYLVANIA, ASSIGNOR TO ERIE STEEL CONSTRUCTION COMPANY, OF ERIE, PENNSYLVANIA, A CORPORATION OF PENNSYLVANIA.

MATERIAL-HANDLING APPARATUS.

Application filed February 27, 1925. Serial No. 12,039.

In handling material such as aggregate for concrete batches there is usually a supply bin and a batch box receiving its supply from the supply bin. The material is passed from the supply bin to the batch box and then cut off by a gate so that the batch box may be dumped independently of the supply bin. The batch in the batch box ordinarily requires very accurate measurement and the sizes of aggregate obstruct in most structures the closing of the gate. With the present invention the free movement of the gate is provided for because any material which may be pushed to one side in the closing of the gate is caught and carried into the batch box. Features and details of the invention will appear from the specification and claims.

The invention is illustrated in the accompanying drawings as follows:—

Fig. 1 is a vertical section on the line 1—1 in Fig. 2.

Fig. 2 an end elevation of the device.

Fig. 3 a plan view of the gate carrying roller.

Fig. 4 a side elevation of the same.

1 marks the supply bin. This has the discharge opening 2 which is controlled by a gate 3. The supply bin is carried by the channels 4 supported by a suitable frame. The gate has the upturned edges 5. An angle iron 6 is secured to the upturned edges having one side of the angle extending outwardly and these outwardly extending plates are supported by rollers 7. The rollers 7 are pivoted on pins 7^a carried by the channel 4 and a strap 8 secured to the channel. The gate is handled by a link 9 from any convenient point of support.

40 The receiving box 10 is ordinarily carried by rods 11 by means of which it may be adjusted. It has the contracted top 12 with the flaring receiving opening having the angle sides 13 and 14, the side 13 being positioned relatively to the opening 2 to receive all the material coming from the bin through the opening without loss of material over the top of the side 13, in other words, it is so related with relation to the angle of repose and its distance from the discharge opening 2 so that the flow of material through the discharge opening is stalled by the filling of the batch box 10. The side 14 is more extended laterally than 45 the side 13 and a partition 15 is arranged in

a position corresponding to the side 13 and in a position to receive the material coming from the opening 2, the part between the partition 15 and side 14 in effect forms an auxiliary opening 16.

50 The gate slides closely under the lip 2^a of the wall of the opening 2. The other walls of the opening 2, however, do not extend down into contact with the gate 3 so that as the gate is moved from open position to closed position there is no obstruction to its forward movement close enough to result in the wedging of the particles of aggregate along the front edge of the gate. As the gate is forced forward, however, 55 through the pile of aggregate between the discharge opening 2 and the receiving opening a small amount of the material will be pushed forward with the gate and in the present invention this is carried over the 60 edge of the partition 15 and deposited in the auxiliary passage 16.

65 In this way the least possible obstruction is opposed to the closing of the gate. The amount of material pushed over is almost 70 exactly the same with each closing so that accurate measuring is accomplished and any material pushed over is caught and received by the batch box so that there is no accumulation of this material from one batch to 75 another, or deposit other than in the batch box.

80 What I claim as new is:—

1. In a material handling apparatus, the combination of a supply bin having a discharge opening; a gate controlling the opening; and a batch box having a receiving opening registering with and adjacent to the discharge opening and having an auxiliary opening separated by a partition from the receiving opening adapted to receive material pushed over in closing the gate and delivering the same to the box.

2. In a material handling apparatus, the combination of a supply bin having a discharge opening; a gate controlling the discharge opening; and a batch box having a hopper-shaped receiving opening registering with and adjacent to the discharge opening and having an auxiliary opening 95 separated by a partition from the receiving opening adapted to receive material pushed over in closing the gate and delivering the same to the box.

3. In a material handling apparatus, the 100

combination of a supply bin having a discharge opening; a gate controlling the discharge opening, said gate being in sliding engagement with the side of the discharge opening toward which the gate is opened and spaced from the wall of the discharge opening toward which the gate is closed; and a batch box having a receiving opening registering with and adjacent to the discharge opening and an auxiliary opening

at the side of the receiving opening toward which the gate is closed, said auxiliary opening being separated from the receiving opening by a partition and receiving material pushed over in the closing of the gate and 15 delivering the same to the box.

In testimony whereof I have hereunto set my hand.

JOHN A. AULD.
